UNITED STATES PATENT OFFICE.

JOHN FERNIE, OF PHILADELPHIA, PENNSYLVANIA.

VENTILATING APPARATUS FOR ROCKING-CHAIRS.

SPECIFICATION forming part of Letters Patent No. 322,705, dated July 21, 1885.

Application filed July 23, 1883. (No model.)

To all whom it may concern:

Be it known that I, JOHN FERNIE, a subject of the Queen of Great Britain and Ireland, and a resident of Philadelphia, Pennsylvania, have invented certain Improvements 5 in Cooling and Ventilating Apparatus, of which the following is a specification.

My invention consists of a certain improvement in that class of cooling and ventilating 10 devices in which a rocking-chair is provided with bellows apparatus and a blast pipe or conduit for projecting a stream or streams of air onto the person occupying the chair.

My improvement comprises means for 15 steadyng and equalizing the force of the blast and for insuring a thorough cooling and ventilating effect due to the blast.

In the accompanying drawings, Figure 1 is 20 a vertical section of a rocking-chair with my improved cooling and ventilating device, and Fig. 2 a rear view of the same.

A is a rocking-chair of ordinary construction, with which is combined a bellows structure comprising the two bellows-boxes *a*, *b*, 25 having hinged flaps *d* and inlet-valves *e*, and communicating with the expansion or pressure chamber *f* through openings provided with outlet-valves *g*, the bellows *a* being contracted on the forward movement of the chair and 30 the bellows *b* on the backward movement of the same, so that a continuous flow of air into the pressure-chamber *f* is caused.

The flaps *d* may be so heavy as to fall by 35 their own weight, as also may the top of the pressure-chamber *f*, or the latter may be acted upon by springs, as shown, and each flap *d* is preferably furnished with anti-friction rollers *h* for running on the floor.

The pressure-chamber *f* communicates 40 through a passage, *i*, in the bellows-box *b* with a pipe, *B*, secured to the back of the chair,

preferably in the center, and the upper end of this pipe is bent over the chair-back so as to discharge the air upon the head and face of the occupant of the chair. In order, however, to provide for a more extended agitation 45 of the air of the apartment, and consequently a better ventilating effect than would be caused by the discharge of the air directly from the end of the pipe, I combine with said pipe a 50 reaction-wheel operated by the blast and carrying fan-blades, as shown, whereby the escaping blast is caused to affect the air at and near the mouth of the pipe *B* and thus cause currents in the room or apartment in which the 55 chair is situated, these currents of air being mingled with the cool blast which escapes in whirling jets from the reaction-wheel, so that not only is the occupant of the chair directly 60 benefited by the draft but the air of the whole apartment is cooled and set in motion.

The combined reaction-wheel and fan is 65 similar to that described in my Patent No. 280,595, dated July 3, 1883, and hence is not claimed, broadly.

I claim as my invention—

The combination of a rocking-chair, two pairs of bellows connected thereto, so as to be operated alternately, a pressure-equalizing box, *f*, receiving the air from both pairs of 70 bellows, a distributing-pipe, *B*, communicating with said equalizing-box *f* and extending to the top of the chair, and a reaction-wheel carried by the upper end of the pipe and provided with fan-blades, as set forth.

In testimony whereof I have signed my name to this specification in the presence of two subscribing witnesses.

JOHN FERNIE.
